UNITED STATES PATENT OFFICE.

WILLIAM A. RUSSELL, OF YONKERS, NEW YORK.

AIR VALVE.

Application filed December 15, 1921. Serial No. 522,478.

This invention relates to certain improvements in air valves for steam radiators and the like.

These valves are used with steam radiators 5 to provide communication between the radiator and the outer air, and it is the function of these valves to permit escape of air in the radiator to the atmosphere, the valve closing after the air has been driven out to 10 prevent discharge of the steam through the valve.

These valves must work with great quickness and there must be a good circulation through the valve casing after the valve is 15 closed so as to prevent the valve from waterlogging. The valves and their operating mechanism are positioned in a casing which is secured to the radiator, the casing projecting from the radiator, and as heretofore 20 constructed are of considerable height, so that they are conspicuous and therefore unsightly and are very liable to be hit and injured by careless moving of furniture or the like.

25 It is one object of the present invention to produce a valve casing and valve operating mechanism which shall be small and compact and form a thin flat construction so as to be comparatively inconspicuous when in 30 place on the radiator wall, and which will lie so snugly against the radiator wall as to reduce the liability of being hit and consequently injured to a minimum.

It is a further object of the invention to 35 produce an air valve so constructed as to provide a more efficient circulation through the valve than is the case with these valves as heretofore constructed so as to make the valve practically free from waterlogging.

40 It is a further object of the invention to produce a valve and operating mechanism therefor, which shall be simple in arrangement, the valve moving to opening and closing position accurately and quickly, and the parts not liable to get out of adjustment.

With these and other objects not specifically referred to in view, the invention consists in certain novel arrangements, parts and combinations, which will be described 50 in detail in connection with the accompanying drawings, and the novel features pointed out in the claims hereunto annexed.

In these drawings—

Figure 1 is a vertical section of the valve

and its operating parts shown secured to the 55 radiator wall, the latter being shown in section and broken away.

Figure 2 is a cross sectional view taken on the line 2—2 of Fig. 1.

Figure 3 is a side view partly in section of 60 the valve casing, the view being taken looking toward the left in Fig. 1.

Figure 4 is a sectional view showing a modified valve operating mechanism.

Figure 5 is a top view of the thermostat 65 strip shown in Fig. 4.

Figure 6 is a sectional view of a further modified form of valve operating mechanism which may be employed under some circumstances.

Figure 7 is a cross sectional view similar to Fig. 2, showing a further modification which may be employed and also illustrating an improved thermostatic strip.

Referring now to these drawings which illustrate a preferred embodiment of one of the important features of the invention, to wit,—the small thin flat valve casing and parts, there is shown a casing formed to be quite inconspicuous when on the radiator, and this casing is marked generally with the numeral 1. This casing preferably is as shown, circular and includes a front wall 2 and a back wall 3. These walls are spaced apart to provide a chamber for the accommodation of a valve and valve operating means of sufficient size to function under conditions of use, the resultant structure thus being comparatively thin when looked at edgewise, being in general configuration 90 something like a watch. These intervening edge walls are marked 4, and may be conveniently formed by turning in the walls 2 so as to lie at right angles to these walls and then bending the inner edges to form a 95 flange indicated by the numeral 5, which forms a seat against which the back wall may be secured as by soldering, or in any other suitable manner, so as to make a joint tight against air and liquid. These edge 100 walls 4 may, of course, be of different widths, but they will be preferably made as shown to produce the flat structure relatively narrow, as compared with the width and height of the front and back walls. The edge walls 105 are, as shown, perforated at the top to form a screw threaded opening 6 which receives a nipple 7 having an outlet port 8, this nip-

ple being provided with a threaded shank 9 by which it may be screwed into the edge walls.

The casing is provided with means for securing it to a radiator wall so as to lie snugly against the wall and thus be out of the way and inconspicuous. These means in the particular construction illustrated are in the form of a projection 10, threaded as indicated at 11, to screw into a boss 12 conveniently formed on the wall of the radiator, this projection 10 being preferably formed integrally with the back wall or plate 3, before referred to.

15 The invention includes a valve and valve operating mechanism for closing the casing to prevent steam and water of condensation from passing out therethrough. As shown, this valve is in the form of a pin 13 having 20 a pointed end 14 which enters into the port 8 in the nipple 7, before referred to. In these valve structures the valve should operate very quickly so as to prevent steam from passing out through the valve casing after 25 the air has been expelled from the radiator. Furthermore, there should be provided means for operating the valve to prevent water of condensation from passing out of the casing.

30 While various constructions may be employed for effecting this, in the particular construction illustrated, this valve is secured to a float 15, which is, as shown, an air tight chamber, the walls of which may be 35 made of a suitable light metal. This float is, in the preferred construction, like the casing made as thin and flat when looked at edgewise as possible, and is dimensioned to operate to lift the valve to its seat in the 40 nipple under conditions of use. To enable the valve to operate with great quickness, the valve is preferably operated by a strip of thermostatic metal which will be almost instantly affected by entrance of steam into 45 the valve casing to a sufficient extent to cause a closing movement of the valve. This thermostatic metal may be either in the form of two strips 16 and 17, as shown in Figs. 1 and 2, or a single strip 18, as 50 shown in Figs. 4 to 6. This thermostatic metal may be secured in the casing in various ways, and means are provided for guiding the lower end of the float which may be somewhat varied in detail.

55 Referring first to Figs. 1 and 2, there is shown a supporting strip 19 dimensioned to snugly fit in the casing against the inner face of the front wall 2. This supporting strip at its bottom is provided with feet 20 formed by turning in the ends of the strip, a supporting flange 21 extending between the feet but somewhat above them so as to leave a space between the flange and the edge wall 4 of the casing. This flange is 60 apertured to receive a guide pin 22 secured

to the bottom of the float. The upper end of the supporting strip 19 is also formed to provide a perforated extension 23 to which one end of each of the thermostat strips 16 and 17 are secured by rivets 25 at each side, and the perforation is arranged to receive the threaded shank of the nipple 7. With this construction the support 19 with the strips secured thereto and the pin 22 positioned in the flange 21, may be assembled and the whole slipped into the casing and held in place when the nipple is screwed into position.

In the constructions shown in Figs. 1, 2 and 6 the free ends of the thermostat strips are arranged to bear against the thin edge of the float and lift the float to close the valve, and to enable this to be effected the float is, as shown, provided with a flat bottom indicated by the numeral 27.

In the modification shown in Fig. 6, the support 19 is omitted and the guide for the lower end of the valve may be formed by the thermostat strip itself. In the construction here illustrated, there is provided a single strip which is bent up centrally, as indicated at 28 to provide a recess to receive the end of the guide pin 22, the strip being secured as by rivets 29 to the casing walls, one of these rivets being provided on each side of the bent up portion 28. In this construction, as in the construction shown in Figs. 1 and 2, the free ends 30 of the strip bear against the flat bottom 27 on the float to operate the float.

In Figs. 4 and 5 is illustrated a further modification. In this construction there is provided a single thermostat strip which is secured in place by rivets 31, which pass through extensions 32 on a metallic bridge shaped member 33 which is apertured to receive guide pin 22. The free ends 34 of the strip are slotted to overlap, as shown in Fig. 5. The shank of the valve 13 is positioned in these slots and is provided with a lifting collar 35 against which the ends of the strips bear. With this construction the valve and float are lifted by the expanding movement of the strip to close the valve.

The invention also includes an improved means for bettering the circulation through the valve casing as compared with valves as heretofore constructed. While these means will preferably be used with the flat casing, as heretofore described, such means are capable of use with casings and valves other than those shown, and the invention as to this feature is not to be limited to the casing, valve and valve operating means described.

This improved circulation is effected by taking advantage of the different temperatures within and without the valve casing, and a passage for the steam and air from the radiator to the casing is provided which is located on the outside of the casing.

While this passage may be formed in various ways, as illustrated there is formed on the outside of the back wall 3 of the casing a passage of sufficient dimensions for the purpose required, the walls of this passage being preferably formed integral with the back wall. This passage is indicated by the numeral 36, the inner wall of this passage being formed by the back wall 3 of the casing, and the outer wall indicated at 37 being integral with the casing. In the particular construction illustrated, this passage extends at one end through the projection 10, before referred to, this projection being divided by a central wall 38 formed integral with the back wall 3 of the casing, and this passage extends from the interior of the radiator outside the casing and is connected with the interior of the casing by an opening 39.

Water of condensation is taken off by a short pipe 40 which extends through the projection 10 so as to open into the casing near the bottom, and this pipe is united by a coupling 41 with a pipe 42 extending down into the radiator. This construction forms a siphon by which the water of condensation is taken out of the valve casing.

In Fig. 7 there is shown a further modification of the improved valve which may be employed under certain circumstances, particularly where a greater valve movement is necessary or desired than would be taken care of by the single thermostatic strips shown in the other figures, and there is shown in this Fig. 7 an improved thermostatic strip for effecting a wide valve movement. In the particular construction shown, the valve casing and the float may be arranged and constructed substantially in the same manner as already described with reference to Fig. 2. This float is, however, in the construction illustrated in Fig. 7, operated by a thermostatic strip of improved construction whereby a very effective lifting action on the float is obtained. As there shown, there is provided a pair of thermostatic strips, each strip comprising two members 36, 37 secured together at one end, these strips being separated at the other end. One of these members, as the member 36, is secured at one end by rivets 38 in the extensions 20 of the supporting strip 19 before referred to. The free ends of the other member 37 bear against the flat bottom 27 formed on the thin edge of the float. While the thermostatic strips could be formed by bending a long strip to form the two members 36, 37, it has been found in practice that the best results are obtained by providing two strips and uniting them at one end, as by rivets 39. With this construction it will be seen that the upper ends of the thermostatic strips exert a lifting action until they are stopped by the walls of the casing, the upper end being free to move in the casing. After further

expanding movement of both strips is prevented by the casing walls, however, a continued expansion of the strip member 37 causes a further lifting action of the float, and thus acts to give the float a wide lifting movement and hold the valve snugly closed. While one such double thermostatic strip might be used, it has been found in practice that a more even movement is obtained by the use of two such strips, one bearing against each side of the flat bottom on the float, as shown in Fig. 7, and this construction will preferably be used.

With this construction the steam from the radiator enters the casing through the passage and as the temperature in the casing is higher than that of the passage outside the casing, a circulation of steam is set up in the casing, which acts to help the siphon free the casing of the water of condensation, so that the valve will be free from water-logging and will function effectively under all conditions.

While the invention has been shown and described in its preferred form, it will be understood that certain changes and variations may be made in the specific form and construction, and that the invention is not to be limited to the precise casing and valve and valve operating means shown. It is further understood that the invention as to the feature of the outside passage is not to be restricted to the type of casing shown, but it may be used in other types of air valves.

What I claim is:

1. In an air valve, the combination of a casing having spaced front and back walls the intervening edge walls being comparatively narrow as compared with the width and height of the front and back walls so as to form a thin flat structure, a valve in the casing, a valve seat for the valve, a support in the casing and means for holding it in position, a float in the casing connected with the valve and guided at one end on the support, a thermostatic strip arranged for free travel co-operating with the float, and means for securing the casing to a radiator.

2. In an air valve, the combination of an annular casing and means for securing it to a radiator, a valve in the casing, a removable seat for the valve, a removable support in the casing and means for holding it in position, a float connected to the valve and guided at one end in the support, and a thermostatic strip arranged for free travel secured to the support and co-operating with the float.

3. In an air valve, the combination of an annular casing and means for securing it to a radiator, a valve in the casing, and a thermostatic element arranged for free travel for operating the valve, said element including two members united at one end, one of

said members being secured to the casing and the other of said members operating the valve.

4. In an air valve, the combination of an annular casing and means for securing it to a radiator, a valve in the casing, and a thermostatic element arranged for free travel for operating the valve, said element including two separate strips secured together at one end, one of said strips being secured to the casing and the other of said strips operating the valve.

5. In an air valve, the combination of an annular casing and means for connecting it to a radiator, a valve in the casing, a float for operating the valve, and a thermostatic element arranged for free travel for operating the float and including two sets of thermostatic strips, each set including a member secured to the casing and a member which engages with the float for operating it.

6. In an air valve, the combination of an

annular casing and means for securing it to a radiator, a valve in the casing, a float in the casing, and a pair of thermostatic elements for operating the float, said elements each including two strips united at one end and extending around the float one of the strips being secured to the casing and the other of said strips bearing against the bottom of the float.

7. In an air valve, the combination of an annular casing and means for securing it to a radiator, a valve in the casing, a float in the casing, and a pair of thermostatic strips on each side and extending around the float, the strips of the pair being secured together at their upper ends, one end of one strip of each pair being secured to the casing and the other end being upwardly bent to engage the bottom of the float.

In testimony whereof, I have hereunto set my hand.

WILLIAM A. RUSSELL.
